UNITED STATES PATENT OFFICE

ALBERT P. BALL, OF DETROIT, MICHIGAN, ASSIGNEE TO SQUARE D COMPANY, OF DETROIT, MICHIGAN, A CORPORATION OF MICHIGAN

UNIT BASE CONSTRUCTION

Original application filed July 19, 1920, Serial No. 397,261. Divided and this application filed March 7, 1923. Serial No. 623,356.

My invention relates to electrical apparatus such as switches and other devices of analogous character in which conducting members or current-carrying parts are mounted upon insulating bases or blocks.

My invention relates more particularly to the construction of these insulating bases or blocks, and the manner in which the conductor members are carried thereon.

10 It will be apparent, as the description proceeds that my invention is not to be limited to any particular type of electrical apparatus, as it may be used to advantage in other structures wherein insulating bases 15 are essential, or in non-analogous devices wherein insulating bases are not required, but where the method, disclosed herein, of mounting members upon individual units, and of arranging and holding these units 20 in position upon a supporting wall may be used with equal advantage.

Briefly, the invention in its simplest form comprises a novel method of supporting conductor members or current-carrying parts 25 upon insulating mountings, so that when it is desired to remove certain of the conductor members for replacement, it is not necessary to disturb the remaining conductor members, or the electrical connections thereof.

30 In the construction of switches, the hinge jaws, switch jaws, grounded neutral set-ups, etc., are insulated by a base of insulating material, such as porcelain, slate and the like. Heretofore in the art great difficulty 35 has been experienced in the manufacture of these bases, particularly when the materials above mentioned are used. It is not necessary to take into consideration the dielectric strength of porcelain and slate, as it is 40 extremely high. However, consideration of the mechanical strength of porcelain and slate is necessary. Slate is objectionable in many cases, because of metallic veins being found therein, and furthermore because of the breakage thereof. Again drilling of the slate is expensive. Porcelain is 45 also objectionable as it is fired when it comes from the die or mould, therefore can not afterwards be machined. Consequently it 50 is used mainly in smaller capacity switches.

These difficulties have rendered it difficult in many instances to produce insulation bases of the desired type and size, especially in larger capacity switches where slate is preferable.

It is common, at the present time, to attach the conducting members to the insulation base by means of bolts passing from the back side of the base into the conducting members, the heads of these bolts being sealed over to insulate the same from the back wall of the enclosure. Burning of the terminals and conducting members are common occurrences. When it is necessary to replace these terminals or conducting members, a difficult task is encountered, as it requires first disconnecting the circuit wires, then removing the screws holding the insulation base in order to free the same from the box and obtain access to the back side thereof, and finally, breaking away the sealing compound covering the heads of the bolts which connect the current-carrying members to the base in order that the particular member may be removed. It is by 75 means of this intricate procedure that the part burned was heretofore replaced. The difficulties encountered are obvious.

My invention involves a departure from the principles involved in the prior art method and eventuates marked advantages, resulting in a saving of material as well as facilitating the removal of conducting members when replacement thereof is necessary. Aside from these features, the invention 80 greatly reduces the cost of manufacture in many respects. It is obvious that where service requirements, as numerous as they are, require different sizes and types of bases for practically every size or kind of apparatus employed, a large stock of raw material is necessary, if not a large stock of finished material as well. For each size of switch or different apparatus, finished bases in stock are necessary, which requires manufacturers to burden themselves with added overhead in the form of additional stock, the majority of which is really unnecessary and accumulates either through a desire to reduce 85 production cost to a minimum or through 90 95 100

what may be termed a necessity, namely, of furnishing any type of mounting on short notice, such as in cases of emergency.

Primarily, the object of my invention is to obviate the above disadvantages and includes the provision of an improved method of and means for, positioning the conducting members or current-carrying parts upon individual insulating mountings, and for maintaining the latter properly positioned upon the back wall of a switch enclosure, or other form of supporting means. A further object is to provide a novel individual mounting for each conducting member in the form of a base unit capable of individually mounting upon said back wall; as well as a novel method of assembling these current-carrying parts and insulating bases so that they may be individually secured to, and detached from, the front of the switch without dismantling the switch.

Another object is the provision of a novel, simple and improved means for securing the base units in place in a variety of patterns in order to obtain various types of switches, although one form only of base unit may be used. However, my invention also provides for forming these base units in a variety of shapes and designs in order to increase the flexibility of this adaptation and permit unlimited use of them in this and similar constructions. In some switches, I contemplate embodying the aforesaid base unit securing means in the form of an apertured grid which lies over and down upon each base unit in a gripping contact, while in other switches, lateral flanges are contemplated, which flanges will receive the bolts for attaching the contacts to the back wall of the enclosure. In each instance, substantially the same advantages accrue.

A further object of my invention is to provide a simple and improved means for securing the conducting members or current-carrying parts to these base units, so that the replacement of a conducting member will require a minimum amount of time and labor. This is one of the important features of my invention, as it eliminates what was heretofore required, viz., dismantling the switch base in order to obtain access to the back side for breaking away a compound covering the head of the bolt securing the particular part to be replaced.

The following advantages are the result of my invention:

(a) Ability to replace a conductor member or terminal without dismantling the entire switch or other apparatus embodying my invention;

(b) Reducing the replacement cost when any part breaks, in that a saving of labor and material is affected;

(c) Universal adaptation of the base units, as their individual character permits

them to provide a wide variety of designs in base construction;

(d) Simplicity of construction, due to the simple design of each base unit;

(e) Economy in manufacture, as the base units are relatively small and easily made; and

(f) Lighter and less cumbersome construction.

I believe that I am the first to provide interchangeable base units moulded of insulating material and held in position either by a grid or by attaching them directly to the supporting wall, and shall therefore claim the same broadly.

In order to apprise those skilled in the art how to construct and practice my invention, I shall now describe various embodiments thereof in connection with the accompanying drawings which illustrate the interchangeability of the base units and the possibility of obtaining a variety of terminal base constructions.

In the drawings:

Figure 1 is a perspective view of a switch box, the cover being removed and the walls partially broken away to disclose in detail my base construction;

Figs. 2, 3 and 4 are perspective views of the backs of switch boxes having mounted thereupon various types of unit-base securing grids;

Fig. 5 is a perspective view of a grid slipped over and engaging the shoulder of several base units;

Figs. 6, 7 and 8 are perspective views of various types of unit-base contact-supporting blocks;

Fig. 9 is an elevational sectional view of a current-carrying assembly mounted on one of my novel base unit insulating blocks;

Fig. 10 is a perspective view of an enclosure illustrating the manner of attaching the base units directly to the back wall thereof;

Fig. 11 is a similar view of the base unit employed;

Fig. 12 is a perspective view of a different form of base unit attached directly to the back wall of the enclosure; and

Fig. 13 is a similar view of this form of base unit.

In the above mentioned drawings and in the hereinafter description of my invention I have shown, and will describe, only so much of the switch mechanism per se as is necessary for an understanding of the structure wherein base units embodying my invention are utilized. It is to be understood, of course, that a supporting surface and a base unit contact block with associated current-carrying parts, said block being secured to said surface either directly or by a grid member fitting over said block, constitute a complete operative embodiment of my

invention. I have found my invention most applicable to the erection of base units for supporting switch contacts, but it may, of course, be applicable to many other uses and it is, therefore, proper only to indicate the character of the mechanism which is supported on the base units. As a matter of fact, a description of the manner in which my improved base structure is embodied in a complete switch is contained in my co-pending application, Serial No. 397,261, filed July 19, 1920, and assigned to the Square D Company. This present application is a devision of said application, Serial No. 397,261 and therefore, all that is shown therein with respect to a complete switching apparatus, is to be considered as a disclosure in this present application.

Referring now to Fig. 1, I have shown, for purposes of illustration only, my unit base structure as positioned in a switch box 10. This box comprises side and end walls 11 and 12, respectively, and a back or bottom 13.

In making up my unit base switches, I utilize a plurality of base unit contact or terminal blocks 14. These individual mounting blocks are positioned in the switch box and are held therein either by a grid-like member which serves to secure them to the back wall, or by screws passing through each of the individual blocks and into the back wall.

In Figure 1, I have shown these terminal blocks as being provided with flanges at the bottom, which in the figure mentioned take the form of peripheral shoulders 16. The blocks may be secured to the back or bottom 13 of the switch box by utilizing the flanges to secure the blocks to the back; and in the embodiment of my invention shown I utilize a perforated grid member 15 which fits down over the blocks and bears against the flanges or shoulders 16 to effect the desired securing of the blocks to the box. I find that this method of securing the blocks may, under some circumstances, be preferable to another method which I hereinafter describe more in detail; that is, one in which screws are passed directly through the flanges and into the back of the box. In either case the heretofore mentioned advantages of the individual base unit terminal blocks are realized.

The blocks 14 are of insulating material and I find it advantageous in either of the above cases to provide them with a metallic threaded insert 18, which is set into the top or front of the blocks. Reference may be had to Fig. 9 for a clearer showing of the manner in which these threaded inserts are utilized to so secure the current-carrying parts to the front of the block that certain of the advantages, heretofore, enumerated, are realized.

The current-carrying parts mounted on the block shown in this figure comprise a switch contact 19 and wire connector 19a; both of the latter being mounted on a flat piece 19b by means of bolts and nuts 19c and 19d, 19e and 19f, respectively. The flat piece 19b is secured to the front of the block by a screw 20 which passes therethrough and into the threaded insert 18 from the front.

These parts may be assembled either by first mounting the members 19 and 19a on the flat piece 19b by means of the bolts and nuts as shown, and thereafter securing the current-carrying assembly to the front of the insulating block 14 by the screw 20; or the flat piece 19b may be secured to the front of the block 14 by the screw 20, the bolts 19c and 19e being first secured to the flat piece 19b by small portions of solder 19g and 19h, respectively, securing the flat piece with its attached screws to the block 14, and thereafter placing the parts 19 and 19a down over the projecting shanks of the screws and tightening the nuts 19d and 19f.

By utilizing the method just described of mounting and assembling the current-carrying parts upon the insulating base unit 14, marked advantages result because one is then enabled to secure the current-carrying parts to, and detach them from, the front of the block, and consequently the front of the switch, individually and without dismantling the entire mechanism.

I believe that this method of mounting current-carrying parts on insulating bases is novel, and since it eventuates certain advantages I hereinafter claim the said method broadly, it being noted that said current-carrying parts are separately mounted on the individual bases of insulating material so that any one of said parts can be quickly removed without interfering with, or dismantling, the other operating portions of the switch whereby rapid, easy, and inexpensive part renewal is assured.

In Fig. 1, I have shown a very simple form of switch mechanism mounted on these base units. As shown, movable blades 21 are adapted to bridge the contacts mounted on the blocks, these blades being connected by a cross-head 22. While, as I have pointed out, this showing of the switch mechanism is conventional because it forms no part of my invention, it will nevertheless be observed, that I have shown a mechanism which comprises a completely operative structure.

Referring now to Fig. 2, I have illustrated a base member or grid 23 which is differently perforated from the grid 15 in that there are six rectangular openings, instead of four, which are arranged in tandem relation of two rows of three openings each. As illustrated, this particular type of grid may

be utilized with the base units 14 to build up a switch structure wherein fuses (not shown) may be utilized. Of course, the base unit apertures may vary in size as may also the base units. This, however, is a matter of desirability, and is in no wise a departure from the spirit of the base unit construction. As a matter of fact, I have shown base units associated with the grid 23 which are constructed in accordance with the disclosure of Fig. 8. These base units are substantially the same as those of Fig. 6, but the tops thereof are differently shaped to accommodate the contacts or terminals mounted thereupon.

In Fig. 3, I have shown another type of perforated grid, it being noted that here the middle perforations are at right angles to the others. As shown, this base is particularly adaptable for the reception of switch mechanism of the double throw type.

In Fig. 4, I have illustrated still another base structure in which base units, such as 14, may be utilized. Here, however, two of the base units are arranged in a laterally extending direction across the middle of the base and a switch mechanism of a particular character is mounted thereupon. I illustrate this last grid and the method of utilizing it with two laterally extending contact blocks in pairs to emphasize to what extent my invention is flexible to take care of practically any desired type of base construction. In this disclosure, one side of the switch is shown so that it will be apparent how this particular arrangement of base units is useful in assembling the terminals of a switch. Base units 14 constitute the mountings which carry the terminal clips of a cartridge fuse 30. The central base unit 14', being at right angles to the outer base unit 14', electrically connects with the other central base unit 14'', by a conducting strap 31 secured to conductor bars 32 by screws 33. Each base unit is provided with a bar 32 which fastens thereto by screws 20 threading into inserts 18, as described in connection with Fig. 1. Screws 33 serve also to hold wire connections 34 to each base unit. The switch terminal clips 35 are carried on base units 14'' in a similar manner, the inner base units being arranged transversely to the outer ones, in this particular instance, for the purpose of receiving conducting strap 31. The above description is given to illustrate the utility of the base units in carrying variously arranged electrical conducting members. It being of course understood that this utility extends to different devices as well.

With reference to the disclosure of Fig. 4, it may be pointed out that the base units are preferably moulded to result in the finished form herein shown. Inserts 18 are either set in the mould or later inserted and

retained by a tight fit. End recesses or grooves 35' are provided so that when the screws 32 and those which hold the terminal clips to conductor bars 32 are threaded down, a resulting clearance is provided to receive the ends thereof (in Fig. 9 the screws 19c and 19c extend into these clearances). This is particularly useful in this construction as it allows for any slight variation in the length of the screws. Inasmuch as the various parts constituting the assembly of a hinged jaw or switch jaw terminal on each base unit are quite thin, having in some instances but one or two threads in the taps provided therein, it is obvious that an undersized screw could not be used, no matter how slight the difference would be. Consequently, provision permitting the use of a slightly oversized screw is desirable.

Referring now to Fig. 5, I have illustrated a grid which is perforated with variously shaped apertures. Three of these apertures may be positioned over blocks of the character shown in Fig. 6, or blocks of different design, having longitudinal flanges along the edges of the terminal carrying face, as shown in Fig. 5. However, in Fig. 7, I have illustrated another type of base unit which may be desirable when it is necessary to mount a relatively complicated conducting member on a base unit. This base unit will be accommodated in the larger apertures of the grid 27.

It will be noted that the base unit shown in Fig. 7 is provided with an elongated recess 36 which is parallel to insert 18 and circular recesses 37. Insert 18, of course, receives the screw securing the conductor bar which carries the various parts constituting, in any particular instance, the clip contact or terminal. Recesses 37 may be located directly beneath screws provided to hold a part or parts which have, more or less, a fixed position with respect to the base unit, while recess 36 is provided beneath a projecting screw of a part having a shifting position. In assembling switch bases, various factors must be taken into consideration. Voltage will control the distance between terminals, and in heavy construction, thickness of certain members will also alter the distance. Consequently, by allowing for such variations in constructing the base units a wider field of adaptation is obtained without requiring a multitude of different designs. The elongated recess 36 will permit the base unit to be shifted slightly, so that it can be made to align with another base unit. It is here pointed out that the apertures in the grid 26 may be cut accordingly, to accommodate any change in the location of the base units, this being accomplished by providing blank grids and allowing the assembly men to cut the apertures as needed.

As before mentioned, in some switches I

utilize the grid flanges in another way to attach each base unit directly to the back wall of the switch enclosure. As shown in Fig. 10, this is accomplished by providing aligned base shoulders or flanges 51 on the opposite longitudinal sides of the base units 50, the flanges having holes 52 provided therein to receive screws 53 which attach directly to the back wall 54 of the switch enclosure 55. The flanges 51, on each base unit, are preferably disposed opposite each other, and are adapted to have a metallic strap 56 laid over their top faces, so that the nuts 57 of the screws 53 will bear against them instead of the flanges 51. Thus the tendency to fracture or crack the flanges 51, as the result of threading the nuts 57 down on the screws 53 too far, is eliminated.

In building up a switch having these base units 50 attached directly to the back wall of the enclosure, any desired spacing between the adjacent units may be easily obtained, and any required arrangement or disposition of them, relative to each other, can be had without difficulty.

In Figs. 12 and 13 I have illustrated practically the same layout of base units. However, in this disclosure, the base units are constructed in a slightly different manner. Instead of the base unit flanges being opposite each other and along the longitudinal sides of the units, these flanges are offset as indicated at 60 in Fig. 13. It is apparent that the usual advantages in offsetting securing or supporting members are obtained herein. Twisting strains are more evenly distributed, and there is less opportunity for the units to disalign from each other, which renders imperfect contact between the blades of the switch and the terminal clip contacts.

Other variously designed base units may be furnished and arranged differently from those described herein if desired.

Without further elaboration, the foregoing will so fully explain the gist of my invention, that others may, by applying current knowledge, readily adapt the same to use under varying conditions of service, without eliminating certain features which may properly be said to constitute the essential items of novelty involved, which items are intended to be defined and secured to me by the following claims.

Having thus described my invention, what I claim as new and desire to secure by Letters Patent in the United States, is:

1. In a switch, a support, terminal blocks, means adapted to fit over and substantially peripherally surround said blocks, and means to secure said last means to said support whereby said terminal blocks are firmly held in relation thereto.

2. In a switch, a support, terminal blocks having inclined sides, a member adapted to fit over and contact peripherally with said

blocks, and means for securing said member to said support whereby the blocks are firmly held in relation thereto.

3. In a switch, a support, terminal blocks having inclined sides, and a perforate member secured to said support, said blocks projecting through said perforate member and being firmly held by the engagement of the edges of said perforations with said inclined sides.

4. In a switch, a casing, insulating terminal blocks having non-parallel sides, and a perforate member secured to said casing, said blocks being firmly seated in said perforations of said members by reason of the engagement of said block sides with said member.

5. In a switch, a casing, insulating terminal blocks having shoulder portions formed thereupon, and a perforate member which is secured to said casing and is fitted down over said blocks, thereby holding said shoulder portions between said casing and itself.

6. In combination, electrical terminal mountings comprising a unit for each terminal, and means common to said units for arranging them in predetermined position.

7. In combination, electrical terminal mountings comprising units for each of the terminals, each unit having a head portion, and a single member for lying over said head portions to hold said units in place.

8. In combination, a support, a plurality of electrical terminal mountings comprising insulation units secured to said support by a single member.

9. In combination, a support, a plurality of electrical terminal mountings, comprising insulation units secured in predetermined spaced relation on said support by a single member.

10. In combination, a support, a plurality of electrical terminal mountings comprising blocks of insulation and a metallic plate for spacing and securing said blocks to said support.

11. Electrical terminal mountings comprising blocks of insulation and a plate for maintaining said blocks spaced by a contractual engagement only.

12. Electrical terminal mountings comprising blocks of insulation and a single member for holding said blocks spaced by lying over a portion thereof.

13. Electrical terminal mountings comprising blocks of insulation for carrying the terminals, said blocks adapted to project partially through a single member for holding them in position.

14. Electrical terminal mountings comprising a support upon which a plurality of blocks are arranged and held in position by a plate-like member.

15. Electrical terminal mountings com-

- prising a support upon which a plurality of blocks are arranged and held in position by a single fastening member having a gripping contact.
16. Electrical terminal mountings comprising a support upon which blocks of insulation are arranged and held in position by a single fastening member having a gripping contact, said fastening member being secured to said support. 70
17. An electrical terminal base comprising a support, a plurality of blocks of insulation loosely arranged on said support, a grid adapted to be laid over said blocks without obstructing terminal faces provided therein for carrying terminal members, and securing means between said support and said grid for holding said blocks in position. 75
18. An electrical terminal base comprising a support having arranged thereon a plurality of blocks provided with terminal faces, and a member having openings substantially of the same configuration as said terminal faces and holding said blocks upon said support. 80
19. An electrical terminal base comprising a support having arranged thereon a plurality of insulation blocks provided with terminal faces, a member having openings through which said blocks project, said openings being substantially of the same configuration as said terminal faces, and securing means projecting from said member into said support. 90
20. In a device of the class described, a support, a plate, a plurality of individual mounts between said support and said plate, said mounts being held in spaced relation by said plate. 100
21. In a device of the class described, a support, a substantially parallel plate-like member, a plurality of individual mounts having portions thereof substantially parallel to said support and said plate, said parallel portions lying between said support and said plate whereby displacement of said mounts is prevented. 105
22. In a device of the class described, a support, a substantially parallel plate-like member, a plurality of individual mounts each having a portion thereof substantially parallel to said support and said plate and a portion transverse to the parallel portion, said parallel portion being disposed between said support and said plate, said transverse portion extending through and lying in projected relation to said plate. 110
23. In a device of the class described, a support, a plate, a plurality of individual mounts carried between said support and said plate, said plate being provided with a plurality of openings through which said mounts project, certain of said openings lying at an angle to the others so that said

mounts may be carried in various positions with respect to each other.

In witness whereof, I have hereunto subscribed my name.

ALBERT P. BALL.
